P. DISERENS.
CONDENSER SYSTEM AND VACUUM PUMP.
APPLICATION FILED MAY 31, 1918.

Patented June 29, 1920.

Inventor:
Paul Diserens
by his Atty's:
Philip T. Murphy & Kennedy

UNITED STATES PATENT OFFICE.

PAUL DISERENS, OF CINCINNATI, OHIO, ASSIGNOR TO WORTHINGTON PUMP AND MACHINERY CORPORATION, A CORPORATION OF VIRGINIA.

CONDENSER SYSTEM AND VACUUM-PUMP.

1,344,994.

Specification of Letters Patent. Patented June 29, 1920.

Application filed May 31, 1918. Serial No. 237,408.

To all whom it may concern:

Be it known that I, PAUL DISERENS, a citizen of the United States, residing at Cincinnati, county of Hamilton, and State of Ohio, have invented certain new and useful Improvements in Condenser Systems and Vacuum-Pumps, fully described and represented in the following specification and the accompanying drawings, forming a part of 10 the same.

This invention relates to improvements in vacuum pumping apparatus, and particularly to an apparatus of this kind for use in connection with condensing systems.

15 In vacuum pump service, especially when used in connection with a condenser, considerable water collects within the pump cylinder and passages. This water is chiefly from three sources, viz., entrained moisture 20 brought over from the condenser with the air; moisture resulting from the chilling effect of the cold jackets of the vacuum pump; and moisture which is precipitated by the compression of the air to atmospheric 25 pressure for delivery.

The object of the invention is to provide a simple, reliable, and cheap vacuum pump capable of maintaining a high vacuum and in which all water from the above mentioned 30 sources is automatically removed from the pump without requiring the use of special drainage attachments for this purpose.

For a full understanding of the invention a detailed description of a construction embodying the same will now be given in connection with the accompanying drawing, forming a part of this specification and illustrating a preferred embodiment of the invention, and the features forming the invention then specifically pointed out in the 40 claims.

In the drawings,

Figure 1 is a side elevation of a condensing plant and vacuum pump embodying the 45 present invention, and

Fig. 2 is a vertical section of the vacuum pump.

Referring to the drawings, 1 indicates a condenser of any suitable type. In the present example it is shown as a surface condenser which may be provided with internal cooling devices for cooling the air as now usual in condenser systems. This condenser is shown as provided with a hot well 2 and at 50 55 3 is indicated a hot well pump which, in

the specific example illustrated, is a centrifugal pump having its suction connected by a pipe 4 to the bottom of the hot well, the suction side of the pump also being connected by an air pipe 5 to a suitable point of the 60 condenser, as for example to the upper part of the hot well, in order that any air accumulating on the suction side of the pump may escape to the condenser. At 6 is indicated a suitable means for circulating condensing water through the condenser. In the present example this means is shown as a centrifugal pump having its suction at 7 and its discharge to the condenser at 8. The cooling water after passing through the condenser is discharged at 9. At 10 is indicated 65 the exhaust steam inlet to the condenser, and at 11 the air discharge pipe.

The above condenser system is that shown and described in United States Letters Patent No. 1,196,742, to M. Riesner, granted August 29th, 1916, and the present invention has been made in connection with the system of said Riesner patent and provides an improved vacuum pump for use in such systems.

For the purpose of removing the air or uncondensable gases and uncondensed vapors from the condenser and thereby maintaining the necessary vacuum in the condenser, 85 the vacuum pump of the present invention is provided, with which pipe 11 connects.

This pump is a vertical pump, and in the form shown comprises a single vertical cylinder 12, having at its upper end an inlet 90 chamber 13 connected to pipe 11 and provided with suitable downwardly opening valves 14, which may be of any suitable light type, preferably such as described and claimed in Meyer Reissue Patent No. 13,991, 95 dated October 12, 1915. The piston 15 carried by piston rod 16 is provided with suitable downwardly opening transfer valves 17, controlling transfer passages 18 through the piston, preferably of the same type, as 100 105 are the outwardly opening discharge valves 23 at the bottom of the cylinder. Small clearance is secured above the piston, where it is most necessary in the pump shown, by the close contact of the head plate and piston, and, as an aid in securing small clearance space below the piston and clearing the cylinder of liquid, the bottom head of the cylinder 19 is preferably provided with projections, such as the truncated cones 20, 110

entering the corresponding lower portions of the transfer passages below valves 17, and the center portion of the piston enters the coned recess between cones 20, with a 5 drain passage 21 from said recess. The same result without the drain passage, may be secured by putting the valves 17 on the bottom of the piston and having the corresponding projections and recesses on the head plate 10 and upper side of the piston, with the lower side of the piston making close contact with a flat lower head of the cylinder. The discharge valves 23 discharge to annular discharge chamber 22 and discharge pipe 24.

15 The operation of the pump is as follows:—On the downward stroke of the piston 15, air and uncondensed gases and vapors will be withdrawn from the condenser through pipe 11 and downwardly 20 opening inlet valves 14 to the upper portion of the cylinder 12. On the return or upward stroke of the piston 15 this air and vapor will pass through the downwardly opening transfer valves 17 in the piston to 25 the lower portion of the cylinder 12, preferably without substantial compression, and upon the next suction or downward stroke of the piston the same will be compressed and forced out through the outwardly opening 30 discharge valves 23.

By means of the apparatus described, a high vacuum can be obtained in a reliable and economical manner, and due to the construction any water brought over from the 35 condenser or condensed in the pump will flow through the pump from the inlet to the discharge by gravity and will be removed from the bottom of the pump with the air and gases.

40 In the condenser and vacuum pump system shown and described, the two stage operation and advantages pointed out in the Riesner Patent No. 1,196,742, are obtained and all drainage difficulty avoided. The 45 pumps may be used on other condenser systems, however, including those in which the air and water are taken off by a single pump. If the head plate and inlet valves 14 be omitted, the pump will operate as a 50 single stage vacuum pump and will be of value under some conditions.

It will be understood that the invention is not to be limited to the specific construction or arrangement of the condenser system or pump shown, as these may be varied widely without departing from the invention, as defined by the claims.

What I claim is:

1. The combination with a condenser, of 60 a vacuum pump having a vertical cylinder connected to the condenser at the top of the pump, a transfer passage in the piston having downwardly opening valves, and discharge valves in the lower part of the cylinder.

2. The combination with a condenser, of a vacuum pump having a vertical cylinder with its inlet chamber at the top of the pump and connected to the condenser, downwardly opening inlet valves from the 70 inlet chamber, a transfer passage in the piston having downwardly opening valves, and discharge valves in the lower part of the cylinder.

3. The combination with a condenser, of 75 a pump having a vertical cylinder with its inlet at the upper end connected with the condenser, a discharge outlet at the lower end of the cylinder, a transfer passage arranged to permit the transfer of fluid from 80 the upper end of the cylinder to the lower end, a piston, means for reciprocating the piston, and valve mechanism arranged to transfer the fluid from the inlet side of the piston to the outlet side thereof without material compression of such fluid.

4. The combination with a condenser, of 85 a vacuum pump having a vertical cylinder with its inlet at the upper end connected with the condenser, a discharge outlet at the 90 lower end of the cylinder, downwardly opening valves between the inlet and upper end of the cylinder, a transfer passage through the piston having downwardly opening valves arranged to permit the 95 transfer of fluid through the piston without material compression of the fluid, and discharge valves at the lower end of the cylinder.

5. A vacuum pump having a vertical cylinder 100 with its inlet at the upper end, a piston having a passage through it, downwardly opening valves controlling said passage, and discharge valves at the lower end of the cylinder.

6. A vacuum pump having a vertical cylinder with an inlet chamber above the cylinder, downwardly opening valves between the inlet chamber and cylinder, a piston having a passage through it, downwardly 110 opening valves controlling said passage, and discharge valves at the lower end of the cylinder.

7. A vacuum pump having a vertical cylinder with an inlet chamber above the cylinder, downwardly opening valves between the inlet chamber and cylinder, a piston having a transfer passage through it, downwardly opening transfer valves controlling said passage, said transfer valves being arranged to transfer the fluid through the piston without material compression of the fluid, and discharge valves at the lower end of the cylinder.

8. A vacuum pump having a vertical cylinder with its inlet at the upper end of the cylinder, a piston having a passage through it, and downwardly opening valves controlling said passage, and discharge valves at the lower end of the cylinder, said piston 120

and the bottom end of the cylinder being provided respectively with corresponding recesses and projections, and a drain passage from the recess between the projections on the cylinder end.

9. A vacuum pump having a vertical cylinder, with its inlet at the upper end of the cylinder, a piston having a passage through it and downwardly opening valves control-

ling said passage, and discharge valves at 10 the lower end of the cylinder, said piston and one end of the cylinder being provided with corresponding recesses and projections, for the reduction of clearance space.

In testimony whereof I have hereunto set 15 my hand.

PAUL DISERENS.
